UNITED STATES PATENT OFFICE

2,416,538

HYDROTURBINE PUMP

Arthur J. Nelson, San Mateo, Calif.

Application November 4, 1944, Serial No. 561,925

21 Claims. (Cl. 230—79)

1

This invention relates to the so-called hydro turbine pumps in which a multivaned rotor or impeller rotating in a closely fitting housing carries a ring of water or other liquid around, and the housing space is larger than the impeller at one or more places in the diameter so as to cause the rotating ring of liquid to bodily surge radially back and forth piston-like between the impeller vanes and thus set up a pumping action in a regularly enlarging and contracting space created adjacent the hub of the impeller within the ring of liquid.

The invention has for its objects improvements in this type of pump whereby its effectiveness is enhanced, and a construction which permits of readily changing the pump from a single stage unit to a double stage unit.

One feature is the special design of the vanes which form the liquid pockets between the vanes of the rotor.

Another feature is the diverting or cross-over vaned ring which controls the action of the liquid in the pockets.

Another feature is the way the gas is controlled to and from the rotor spaces.

Other features and advantages will appear in the following description and in the accompanying drawings:

In the drawings:

Fig. 1 is an elevation of my improved hydro-turbine pump connected up or "piped" to function as a two stage pump.

Fig. 2 is a perspective view of one of the two rotors or impellers of the pump supported on the pump shaft.

Fig. 3 is a perspective view showing one vane only of the rotor connected to the rotor hub to show the compound form of the rotor vanes, each of which is alike except that the two rotors generally used in one pump are respectively right and left insofar as the vanes are concerned and as will appear in Fig. 4.

Fig. 4 is an enlarged longitudinal cross section of the pump casing and the two rotors taken along the line 4—4 of Fig. 5, and of Fig. 6.

Fig. 5 is a cross section of Fig. 4 taken along the line 5—5 of Fig. 4.

Fig. 6 is a cross section of Fig. 4 taken along the line 6—6 of Fig. 4.

Fig. 7 is an outside unrolled or development view of one of the diverting rings which surrounds one of the rotors.

Fig. 8 is an inside view of the unrolled ring of Fig. 7.

2

Fig. 9 is an enlarged sectional detail of a portion of the valve ring cage.

Fig. 10 shows the inner side of one of the heads of the pump, with part of the inner flange broken away.

Fig. 11 is a plan view of Fig. 1.

Generally described the pump comprises a main body casting taking the form of a cylindrical casing 1 formed with horizontally supporting legs 2, inlet 3, outlet 4, and other pumping passages. The cylinder 1 is closed on both ends by cast metal heads 5, 5' bolted against the ends of the casing as by marginal bolts 6 passing through flanges 7, 8, while carried outward on each of the heads is a suitable bearing 10 supported on suitable end brackets 11 and which bearings 10 rotatably support a central pump shaft 12 which carries a coupling flange 13 on one end to provide for driving the pump, while mounted centrally on the shaft are two rotors the hubs of which are designated 14 and 14' and which are secured to the shaft as by a key 15.

Hubs 14 are tubular and provided with outer end flanges 16, 16' and inner end flanges 11, 11' which are in face contact, while embraced between these end flanges are more or less radially extending vanes 18, 18' between which the piston-like action of the water takes place and provided with outwardly extended portions 19, 19', 20, 20' respectively, to be further described later on.

The interior of the cylindrical casing 1 is somewhat larger in diameter than the outer circumference of the rotor, and fitting within the annular space thus formed between the rotors and the casing shell are two annular members 21, 21', one for each rotor, and herein termed "diverting rings" the functions of which are to provide peripheral spaces at opposite points within the diameter of the casing to permit the revolving ring of water carried around by the blades to surge outwardly at these points due to centrifugal force and to direct this water from one portion (19) of the vanes over to the other portion (20) as the water is forced back again toward the rotor shaft, in quick repetition, to effect the liquid-piston pumping action, as will be more fully explained.

The heads 5 and 5' are relatively thick and are duplicates formed interiorly with certain inlet and outlet flow controlling passages to be described, and surrounding the shaft 12 in the heads are stuffing boxes comprising rings of packing 22 mounted on a sleeve 23 fitting over the shaft 12 in inner abutting relation to the

rotor, and which packing is adapted to be compressed by a suitable gland 24, while the sleeve 23 is adjustable longitudinally of the shaft by means of a collar 25 threaded on the shaft so that a proper small clearance 26 may be determined at the outer ends of both rotors for circulation of sealing water which may be admitted to these clearances from a pipe 27 connected to cored passages 28, 29 the latter of which also feeds sealing water to a spacing spider ring 30 positioned at an intermediate point in the stuffing box. Both ends of the pump being alike in these details.

Returning now to the rotors, one of which (the right hand one of Fig. 4) is shown in perspective in Fig. 2, these are preferably castings and while the vanes 18 which project from the tubular hub 14 are preferably flat and radial for the length of the hub, the outer portions 19 and 20 where the vanes extend to a larger diameter to fit within the diverting ring 21, are for about half their length curved "backwardly" (with respect to the clockwise direction of rotation of the rotor) as at 19 so as to exert a centrifugal pump action on the water, while the remaining or inner half 20 of each vane is curved forwardly, to function as a scoop to return the outwardly thrown water and force it back or down between the vanes toward the hub of the rotor. These two portions of each vane designated A and B in Fig. 3 are connected as by a short web C in this figure for illustrative purposes, but which becomes a ring at the outer diameter of the blades where this transition from rearwardly curving to forwardly curving takes place as all of the vanes are an integrally cast network and in the completed assembly between the rearwardly curved outer edge A of one vane and its forwardly curved edge B there would be the aligned rearwardly and forwardly curved edges of two other vanes, all integrally joined to the others. This will be understood by a glance at Fig. 6 where the edges of one vane A and B are indicated to correspond with the edges A and B of the detached vane shown in perspective in Fig. 3 to give a three dimensional idea of the general form of each vane. It should be kept in mind however that the two rotors are rights and lefts so that their scooping vane portions 20 will be adjacent at the center of the pump to opposite sides of their contacting inner flanges 17, 17'.

Also to be noted is that the outer ends of portions 19 of the vanes are connected (preferably integrally) by a ring or flange 31 which is spaced slightly (for sealing liquid) as at 32 from inner head flanges 33, and between which inner head flanges the two diverting rings 21 and 21' are embraced.

Also formed within the heads 5 and 5' are hollow hubs 34 spaced longitudinally from flanges 33 and which hubs are recessed in conformity with the bore of flanges 33 to receive a valve ring cage 35, in embracing relation with the outer edges of the extending flat portions 18 of the vanes, and which extending portions of the vanes form what may be termed the gas end of the rotor, as it is here where the air or gas to be pumped enters and leaves the rotor. These valve rings (one for each rotor) each have four longitudinal block portions 36 positioned at 90 degrees apart and extending the length of the outer edges of vanes 18 and of a width to each straddle three of the vanes 18 or rather two vane spaces, so that there will be left uncovered two vane spaces between each valve block portion 75

36, all as best shown in Figs. 5 and 10 of the drawings. Also to be noted from these two figures is that covering block portions 36 are radially aligned with and form continuations of four radially disposed ribs 37 which separate the head space into four spaces or quadrants alternately designated "inlet space" and "outlet space" and which will be seen from a consideration of Fig. 5 to be each open to two of the vane spaces between adjacent blocks 36 and which spaces between the vanes 18 form the gas or air inlets and outlets respectively to the pump rotor at opposite quarters.

As both heads are alike, when in place at opposite ends of the double rotor it of course brings the outlet spaces of one head in line (longitudinally of the pump) with the inlet spaces of the other and as the pump is provided centrally at opposite sides with one main inlet 3 and one main outlet 4 suitable cored passageways 3' and 4' formed in the body casting 1 extend longitudinally both ways toward opposite heads where each suitably connects by appropriate ports 33, 39, 40, 41 in the heads with their inlet and outlet quadrants respectively.

As the function of the pump is to force a ring of contained water outwardly with the backwardly curved portion 19 of the vanes at opposite quarters in the revolutions of the rotor to create a suction space adjacent the hub of the rotor at these two quarters when open to the suction or inlet quadrants of the heads, and then force the water back again with the aid of the scooped portions 20 of the vanes to compress and eject the gas at the two opposite quarters when open to the outlet quadrants of the heads, this outward and inward surging of the contained water or "water ring" as used in this type of turbine-pump is controlled in the present design, as previously stated, by the diverting or cross-over rings 21, 21' for the two rotors respectively of the pump. Each of these rings provides at opposite points in the diameter a space defined by an outwardly slanted wall 43 to permit the water to surge outwardly beyond the rotor, and following this (in direction of rotation) an inwardly slanted wall 44 to urge the revolving water inwardly again. However, as the outwardly urged water leaves the rearwardly curved portions 19 of the rotor vanes and the inwardly urged water is received by the forwardly scooped portions 20 of the vanes, it is manifest that means should be provided on the ring 21 to guide the water in the space beyond the rotor from the outwardly moving to the inwardly moving side or strata, and also to prevent the water from moving outwardly from portions 19 of the vanes or inwardly from portions 20 of the vanes except at the two diagrammatically opposite positions where such movement is desired to effect the alternating suction and compression of the gas, air, or other fluid being pumped, within the proper quadrant of the pump rotor vane spaces as explained. Accordingly each diverting ring is provided with circular inner wall portions 45 close to the rotor arranged to close in the rotor at those two opposite areas where the water should not be permitted to come out, and other circular inner wall portions 46 closing off the rotor at those two opposite areas where the water should not reenter the rotor. Besides this the rings are provided with standing ribs or cross-over guiding vanes 47, 48 which are angularly or spirally arranged to guide the outwardly surging water over to the inwardly flow-

5

ing strata. These angularly disposed vanes co-operate with standing inner marginal flange 49 and outer marginal flange 50. The construction and mode of operation will be easily understood by reference to Figs. 4, 6, 7, and 8, the latter two figures being respectively the outer and inner sides of the ring shown flattened out and with the extreme ends of the development shown stepped to permit extension of the slanted cross-over guiding vanes to their extreme ends.

A feature of the water sealing of the moving parts is that the inner faces of the inwardly extending hollow hubs 34 of the heads 5 are each provided with an annular water recess 51 which receives water from sealing water passage 28 and feeds the water to holes 52 in the side of valve ring 35 (see Fig. 9) and which holes communicate with slots 53 in valve ring blocks 36 and through inwardly extending holes 54 directed toward the leading edge of these blocks (see Fig. 5), so that the film of water will be maintained against the inner arcuate surfaces of these blocks close to which the outer edges of the extended rotor vanes 18 pass, and thus seal off the inlet from the outlet quadrant spaces of the heads at these possible points of leakage. Any excess sealing water forced into the pump will simply find its way out with the compressed outlet gas or air and pass out of the outlet pipe 55 to a suitable water separator as indicated at 56 in Fig. 1 and from where the settled water leaves from a pipe 57 from where it may be returned to the sealing water inlet 27 at opposite ends of the pump.

Of course the areas of the rotor spaces, diameter and length of rotor vanes, and size of surge spaces in the diverting rings 21 are so proportioned as to retain within the pump the required amount of water to provide the desired pumping spaces between the rotor vanes adjacent the hubs while always keeping the outer ends of the vanes covered with the water to maintain the water-piston pumping action, as well understood with this type of pump.

When the pump is run as a single stage pump or compressor both rotors receive and discharge the gas or air being pumped from and to the main inlet 3 and main outlet 4 respectively. But when using the two rotors in series as a two stage pump, the gasket (not shown) which is used across the joint 61 where heads 5, 5' join the body casting 1 is left "blind" at points to block off only the outlet passage 4' leading to head 5', and similarly only the inlet passage 3' leading to head 5, and then an outlet pipe 55 is connected to a normally plugged opening 58 from the outlet space of the left side rotor and an inlet pipe 59 is connected to a normally plugged opening 60 to the inlet space of the right side rotor, pipes 55 and 59 preferably having a water separator 56 interposed, all as indicated in Figs. 1 and 11.

Where the finally ejected gas or air being pumped is required to be free from water, a water separator will be used on the final outlet pipe.

While the drawings show a double rotor pump incorporating my improvements, it is evident that the pump may be made with one of the rotors only where half the capacity is sufficient or where no two stage hookup is desired. It is also evident that more than two stages may be obtained by the use of an additional rotor if desired.

One of the advantages of forming the diverting vanes 47 and surge controlling walls 43, 44, etc., as a ring 21 is that it may be angularly adjusted

in assembling to the most efficient setting dependent on the speed which the pump will be run, and then marked and/or secured in such position. Also the relative angular relation of the two rings when using the pump as a two stage pump may be accurately adjusted.

Having thus described my improved hydro-turbine pump and the manner of its operation, what I claim is:

- 10 1. In a hydroturbine pump of the type described, a rotor provided with a plurality of outwardly extending vanes spaced around a hub, said vanes each formed to provide an outer pumping portion adapted to urge the pumping liquid outward and an adjacent outer turbine portion formed to facilitate the reentry of the liquid toward the hub of the rotor, the pumping portion and turbine portion of each blade merging into one continuous straight vane portion at said hub.
- 15 2. In a hydroturbine pump of the type described, a rotor provided with a plurality of outwardly extending vanes spaced around a hub, said vanes each formed to provide an outer pumping portion adapted to urge the pumping liquid outward and an adjacent outer turbine portion formed to facilitate the reentry of the liquid toward the hub of the rotor, the pumping and turbine portions of each vane being integrally connected, and merging into one continuous
- 20 3. In a hydroturbine pump of the type described, a rotor provided with a plurality of outwardly extending vanes spaced around a hub, said vanes each formed to provide an outer pumping portion adapted to urge the pumping liquid outward and an adjacent outer turbine portion formed to facilitate the reentry of the liquid toward the hub of the rotor, the pumping and turbine portions of each vane being integrally connected, and merging into one continuous straight vane portion at said hub.
- 25 4. In a hydroturbine pump of the type described, a rotor provided with a plurality of outwardly extending vanes spaced around a hub, said vanes each formed to provide an outer pumping portion adapted to urge the pumping liquid outward and an adjacent outer turbine portion formed to facilitate the reentry of the liquid toward the hub of the rotor, the outer pumping and turbine portions of each vane being connected by a relatively short web extending transversely of the axis of rotation of the rotor, and the pumping and turbine portions of each vane merging into one continuous straight vane portion at said hub.
- 30 5. In a hydroturbine pump of the type described, a rotor provided with a plurality of outwardly extending vanes spaced around a hub, said vanes each formed to provide an outer pumping portion adapted to urge the pumping liquid outward and an adjacent outer turbine portion formed to facilitate the reentry of the liquid toward the hub of the rotor, the outer pumping and turbine portions of each vane being connected by a relatively short web extending transversely of the axis of rotation of the rotor, and the pumping and turbine portions of each vane merging into one continuous straight vane portion at said hub.
- 35 6. In a hydroturbine pump of the type described, a rotor provided with a plurality of outwardly extending vanes spaced around a hub, said vanes each formed to provide an outer pumping portion adapted to urge the pumping liquid outward and an adjacent outer turbine portion formed to facilitate the reentry of the liquid toward the hub of the rotor, the outer pumping and turbine portions of each vane being connected by a relatively short web extending transversely of the axis of rotation of the rotor, and the pumping and turbine portions of each vane merging into one continuous straight vane portion at said hub.
- 40 7. In a hydroturbine pump of the type described, a rotor provided with a plurality of outwardly extending vanes spaced around a hub, said vanes each formed to provide an outer pumping portion adapted to urge the pumping liquid outward and an adjacent outer turbine portion formed to facilitate the reentry of the liquid toward the hub of the rotor, the outer pumping and turbine portions of each vane being connected by a relatively short web extending transversely of the axis of rotation of the rotor, and the pumping and turbine portions of each vane merging into one continuous straight vane portion at said hub.
- 45 8. In a hydroturbine pump of the type described, a rotor provided with a plurality of outwardly extending vanes spaced around a hub, said vanes each formed to provide an outer pumping portion adapted to urge the pumping liquid outward and an adjacent outer turbine portion formed to facilitate the reentry of the liquid toward the hub of the rotor and an axially extending portion of materially smaller outside diameter to form the gas receiving and discharging end of the rotor.
- 50 9. In a hydroturbine pump of the type described, a rotor provided with angularly spaced vanes therearound, each vane comprising a longitudinally extending substantially flat minor portion projecting from the hub of the rotor, and a major portion of much greater diameter in turn formed for about half of its length with a rearwardly curved portion and for about the other half of its length with a forwardly curved portion.
- 55 10. In a hydroturbine pump of the type described, a rotor provided with spaced vanes arranged to carry out the liquid piston effect common to such pumps, said vanes being stepped down to a reduced diameter at one end of the rotor to form a gas receiving and discharging end.
- 60 11. In a hydroturbine pump of the type described, a rotor provided with spaced vanes arranged to carry out the liquid piston effect common to such pumps, said vanes being stepped down to a reduced diameter at one end of the rotor to form a gas receiving and discharging end.
- 65 12. In a hydroturbine pump of the type described, a rotor provided with spaced vanes arranged to carry out the liquid piston effect common to such pumps, said vanes being stepped down to a reduced diameter at one end of the rotor to form a gas receiving and discharging end.
- 70 13. In a hydroturbine pump of the type described, a rotor provided with spaced vanes arranged to carry out the liquid piston effect common to such pumps, said vanes being stepped down to a reduced diameter at one end of the rotor to form a gas receiving and discharging end.
- 75 14. In a hydroturbine pump of the type described, a rotor provided with spaced vanes arranged to carry out the liquid piston effect common to such pumps, said vanes being stepped down to a reduced diameter at one end of the rotor to form a gas receiving and discharging end.

mon to such pumps, said vanes being stepped down to a reduced diameter at one end of the rotor to form a gas receiving and discharging end, a head on said pump formed with a recess receiving said reduced diameter of the rotor vanes and provided with separated gas inlet and outlet ports, and means cooperating with the reduced diameter vanes controlling admission of gas to some of the vane spaces from the head inlet port and the discharge of gas from other vane spaces to the head outlet ports.

8. In a hydroturbine pump of the type described a rotor provided with spaced vanes arranged to carry out the liquid piston effect common to such pumps, said vanes being stepped down to a reduced diameter at one end of the rotor to form a gas receiving and discharging end, a head on said pump formed with a recess receiving said reduced diameter of the rotor vanes and provided with separated gas inlet and outlet ports, and a valve cage embracing the outer edges of the reduced diameter vanes closing off some of the vane spaces while maintaining other spaces open to receive gas from the head inlet port and still others to the discharge of gas to the head outlet ports.

9. In a hydroturbine pump of the type described a rotor provided with spaced vanes arranged to carry out the liquid piston effect common to such pumps, said vanes being stepped down to a reduced diameter at one end of the rotor to form a gas receiving and discharging end, a head on said pump formed with a recess receiving said reduced diameter of the rotor vanes and provided with separated gas inlet and outlet ports, and a valve cage embracing the outer edges of the reduced diameter vanes closing off some of the vane spaces while maintaining other spaces open to receive gas from the head inlet port and still others to the discharge of gas to the head outlet ports, and means for introducing a sealing liquid between the vanes and the valve cage.

10. In the construction as set out in claim 8 a flange closing the outer ends of the reduced diameter vane spaces.

11. In the construction as set out in claim 8 a flange closing the outer ends of the reduced diameter vane spaces and means for introducing a sealing liquid between the running joints of said flange and also said vanes.

12. In a hydroturbine pump of the type described a rotor provided with spaced vanes arranged to carry out the liquid piston effect common to such pumps, said vanes being formed for part of their longitudinal length in a manner tending to throw the pumping liquid outward, and for an adjacent portion of their length in a manner tending to receive the outwardly urged liquid for inward movement, and angularly arranged guide means arranged around the rotor guiding the outwardly urged strata of liquid angularly over to the inwardly moving strata.

13. In a hydroturbine pump of the type described a rotor provided with spaced vanes arranged to carry out the liquid piston effect common to such pumps, said vanes being formed for part of their longitudinal length in a manner tending to throw the pumping liquid outward, and for an adjacent portion of their length in a manner tending to receive the outwardly urged liquid for inward movement, housing means around the rotor formed to substantially confine the rotor over part of its diameter while providing space outward of the rotor to permit out-

ward surging of the liquid, and liquid guiding vane means arranged to guide the outwardly urged liquid angularly over to the inwardly moving strata.

14. In the construction as set out in claim 13 said housing means comprising a circular shell spaced concentrically about the rotor, and a ring-like cage member fitting within the space between the rotor and the shell and provided with cylindrical wall portions covering the outer ends of some of the vane spaces to prevent outward flow of liquid and others to prevent inward flow of liquid, while preserving other vane spaces open for outward surging of the liquid beyond the ends of the vanes, and still other vane spaces for inward movement of the liquid, said cylindrical wall portions of the ring being spaced about the rotor and staggered axially as required to control the outwardly and inwardly moving strata of liquid.

15. In the construction as set out in claim 13 said housing means comprising a circular shell spaced concentrically about the rotor, and a ring-like cage member fitting within the space between the rotor and the shell and provided with cylindrical wall portions covering the outer ends of some of the vane spaces to prevent outward flow of liquid and others to prevent inward flow of liquid, while preserving other vane spaces open for outward surging of the liquid beyond the ends of the vanes, and still other vane spaces for inward movement of the liquid, said cylindrical wall portions of the ring being spaced about the rotor and staggered axially as required to control the outwardly and inwardly moving strata of liquid, said cylindrical wall portions slanting outwardly at their ends outward of the rotor at spaced regions to provide the liquid surging space beyond the rotor.

16. In the construction as set out in claim 13 said housing means comprising a circular shell spaced concentrically about the rotor, and a ring-like cage member fitting within the space between the rotor and the shell and provided with cylindrical wall portions covering the outer ends of some of the vane spaces to prevent outward flow of liquid and others to prevent inward flow of liquid, while preserving other vane spaces open for outward surging of the liquid beyond the ends of the vanes, and still other vane spaces for inward movement of the liquid, said cylindrical wall portions of the ring being spaced about the rotor and staggered axially as required to control the outwardly and inwardly moving strata of liquid, said cylindrical wall portions slanting outwardly at their ends outward of the rotor at spaced regions to provide the liquid surging space beyond the rotor, and further provided with spirally extending fins for guiding the outwardly urged liquid angularly to the inwardly moving strata.

17. In a hydroturbine pump of the type described a casing member with two liquid-piston type vaned rotors therein in endwise adjacent relation, each of said rotors having an extension of its vanes at the outer end providing gas inlet and outlet spaces between the vanes respectively at spaced points in the circumference of the rotors, a head secured to each end of the casing member formed to embrace the extension of the rotor vanes adjacent the head, said heads being each provided on its inner side with spaced inlet and outlet gas ports, means isolating the gas inlet spaces of the vanes from the outlet spaces and guide the gas respectively

to and from the inlet and outlet gas ports of the head adjacent vanes.

18. In a hydroturbine pump of the type described a casing member with two liquid-piston type vaned rotors therein in endwise adjacent relation, each of said rotors having an extension of its vanes at the outer end providing gas inlet and outlet spaces between the vanes respectively at spaced points in the circumference of the rotors, a head secured to each end of the casing member formed to embrace the extension of the rotor vanes adjacent the head, said heads being each provided on its inner side with spaced inlet and outlet gas ports, means isolating the gas inlet spaces of the vanes from the outlet spaces and guide the gas respectively to and from the inlet and outlet gas ports of the head adjacent vanes and gas passages carried by the casing members connecting respectively the inlet and outlet ports of the heads.

19. In a hydroturbine pump of the type described a casing member with two liquid-piston type vaned rotors therein in endwise adjacent relation, each of said rotors having an extension of its vanes at the outer end providing gas inlet and outlet spaces between the vanes respectively at spaced points in the circumference of the rotors, a head secured to each end of the casing member formed to embrace the extension of the rotor vanes adjacent the head, said heads being each provided on its inner side with spaced inlet and outlet gas ports, means isolating the gas inlet spaces of the vanes from the outlet spaces and guide the gas respectively to and from the inlet and outlet gas ports of the head adjacent vanes and gas passages carried by the casing members connecting respectively the inlet and outlet ports of the heads and said gas passages carried by

the casing each provided with an opening fitted with means for attaching a pipe.

20. In a pump structure as set out in claim 18 means controlling the pumping liquid to provide two suction and two compression surges at each revolution of the rotor, the suction and compression surges taking place alternately at 90° of arc, and said heads each being formed on its inner side with walls providing four quadrant spaces which are alternately connected with the inlet and outlet gas ports of the head.

21. In a hydroturbine pump of the type described a casing member with two liquid-piston type vaned rotors therein in endwise adjacent relation, each of said rotors having an extension of its vanes at the outer end providing gas inlet and outlet spaces between the vanes respectively at spaced points in the circumference of the rotors, a head secured to each end of the casing member formed to embrace the extension of the rotor vanes adjacent the head, said heads being each provided on its inner side with spaced inlet and outlet gas ports, means isolating the gas inlet spaces of the vanes from the outlet spaces and guide the gas respectively to and from the inlet and outlet gas ports of the head adjacent vanes, and gas passage means adapted for connecting said rotors in series as a two-stage pump.
